[57] CLAIM

The ornamental design for a game club with unitary handle, as shown and described.

DESCRIPTION

FIG. 1 is a perspective view of a game club with unitary handle, showing my new design;

FIG. 2 is a reduced rear elevational view;

FIG. 3 is a side elevational view taken at right angles to the view of FIG. 2;

FIG. 4 is a top plan view thereof; and

FIG. 5 is a bottom plan view of the opposite or handle end.

The characteristic feature of my design resides in the particular configuration of the handle and guard means shown.

FIG. 1.

FIG. 2.

FIG. 3.

FIG. 4.
